DESIGN FOR AN ELECTRIC FIXTURE

R. Guy Cowan, Syracuse, N. Y., assignor to Pass & Seymour, Inc., Syracuse, N. Y., a corporation of New York

Application December 16, 1935, Serial No. 60,115

Term of patent 7 years

To all whom it may concern:

Be it known that I, R. Guy Cowan, a citizen of the United States and resident of Syracuse, county of Onondaga, and State of New York, have invented a new, original, and ornamental Design for an Electric Fixture, of which the following is a specification, reference being had to the accompanying drawing, forming a part thereof, and in which:

Figure 1 is a front elevation of an electric fixture showing my new design;

Fig. 2 is a side elevation thereof; and
Fig. 3 is a top plan view thereof.

I claim:

The ornamental design for an electric fixture, substantially as shown.

R. GUY COWAN.
